SUCTION CUP HOLDING DEVICE FOR PAINT CANS

John L. Cussigh, 8116 Regis Way,
Los Angeles, Calif. 90045

Filed May 19, 1975, Ser. No. 578,522

Term of patent 14 years

Int. Cl. D8—05

U.S. Cl. D8—71

FIG. 2.

FIG. 1.

FIG. 3.

FIG. 4.

FIG. 5.

FIG. 1 is a perspective view of a suction cup holding device for paint cans showing my new design;

FIG. 2 is an end view of the device;

FIG. 3 is a top plan view of the same;

FIG. 4 is a side elevational view; and

FIG. 5 is a bottom plan view.

I claim:

The ornamental design for a suction cup holding device for paint cans, as shown and described.
